FIG. 4.

INVENTOR

Manfred Wahl
BY
Cyrus N. Anderson
ATTORNEY.

UNITED STATES PATENT OFFICE.

MANFRED WAHL, OF PHILADELPHIA, PENNSYLVANIA.

COOLING APPARATUS.

1,373,468.

Specification of Letters Patent.

Patented Apr. 5, 1921.

Application filed July 26, 1919. Serial No. 313,543.

To all whom it may concern:

Be it known that I, MANFRED WAHL, a citizen of the United States, and a resident of Philadelphia, in the county of Philadelphia and State of Pennsylvania, have invented an Improvement in Cooling Apparatus, of which the following is a specification.

In the production of many foods and beverages which have to undergo biological changes and where these changes are required to be kept up to the highest state of purity, if products having the desired purity, quality of flavor, etc., are to be obtained, ferments of lactic acid or yeast are used. The isolation and propagation or development of pure cultures of these ferments have heretofore been effected in apparatus which either have been of complex construction or have required special supervision when in use.

In the art of fermentation as heretofore practised with previously known apparatus, the desired results of high character and biological purity in the finished product have not always been maintained. To a large extent the ferments or pure cultures introduced and propagated under difficult conditions have been responsible for this.

In order that the highest practicable degree of purity and resisting power in the propagated ferments may be obtained and maintained, the manufacturer should know and be able to control the source of the same.

In the isolation and development of pure cultures or ferments for use in the fermenting arts, as for instance, in the manufacture of beer, either containing less or more than one-half of one per cent. of alcohol by volume, there have been used heretofore a small receptacle as a starter and a relatively large receptacle as the propagator or developer in which the pure culture is propagated and developed.

It is to the last named receptacle and to the means for enabling its use in a practical or commercial way that this invention relates. I shall not describe the method or routine followed in the isolation and propagation or development of pure cultures because the general method and general routine to be followed are well known to those skilled in the art. Descriptions of methods and routine which may be fol-

lowed can be found in "Practical Studies in Fermentation" by Emil Chr. Hansen.

The invention has for one of its objects to provide a receptacle of such shape that the contents thereof, such for instance, as wort 60 may be cooled relatively quickly.

A further object of the invention is to provide a convenient means for supporting the said receptacle.

A still further object of the invention is 65 to provide a practical and improved means for effecting the cooling of the said receptacle and the contents thereof.

Other objects and advantages of the invention will be referred to in the detailed 70 description thereof which follows or will be apparent from such description.

In order that the invention may be readily understood and its practical advantages fully appreciated, reference should be had 75 to the accompanying drawing in which I have illustrated one form of embodiment of the same. It will be understood, however, that changes in the details of construction may be made within the scope of 80 the claims without departing from the said invention.

In the drawing:

Figure 1 is a top plan view of the apparatus embodying my invention; 85

Fig. 2 is a side elevation of the same;

Fig. 3 is an edge elevation, said figure being taken in a direction at right angles to that in which Fig. 2 is taken; and

Fig. 4 is a detail view showing means for 90 applying a cooling liquid to the exterior surface of the propagating or developing receptacle.

In the drawing, I have shown a support 95 for the receptacle, said support comprising or including four legs 1 as shown, these having at their lower ends rollers 2 by means of which the said support, together with the receptacle containing the wort or other nutriment in which the pure culture is being 100 propagated or developed, may be transported readily. The opposing end legs are connected together by means of cross bars 3, the latter being connected by means of cross bars or plates 4. To the upper ends of the 105 legs 1 a frame-like oblong shaped tubular member 5 is secured. One of the legs which I shall designate 1^a is tubular and is provided with a pipe connection at 6 by means of which cold water or other cooling liq- 110

uid may be supplied. The liquid thus supplied flows into the tubular member 5 which is of oval shape in plan and escapes therefrom through the perforation 7 upon the lower, inner side of the same. The small streams of liquid escaping from these holes strike the sides of a receptacle or container 10 which is of oval shape in cross section. The receptacle 10, or propagator, as it is called in practice, is supported upon the cross bars 3 and 4.

The receptacle or propagator 10 is closed by means of a lid 12 having an opening 13 at its center. The latter should remain open during the cooling operation, but thereafter should be closed so as to prevent contamination from external sources. The lid is provided with handles 17.

At its lower end the apparatus is provided with a spigot 18 having a valve 19 by means of which the opening through the spigot may be opened and closed. The outer end of the spigot is adapted to be closed by means of a cap 20 so as to prevent, as far as possible, contact of the air with the lower end and the interior of the said spigot. The employment of the cap is for the purpose of preventing contamination as far as may be possible.

The receptacle or propagator 10 preferably is constructed of copper, lined with tin, but it will be understood that my invention is not limited to the material of which the said receptacle is constructed.

In the use of the apparatus, the receptacle or propagator 10 is sterilized and rendered chemically clean. Thereafter the wort or other liquid nutrient in a hot state is introduced thereinto. The temperature of the wort or other nutrient should be sufficiently high to destroy all infectious bacteria or contamination. After the introduction of the wort or other liquid nutrient, the lid 12 is closed, leaving the opening 13 at its center open. Thereafter cold water is allowed to flow through the tube 1^a into the oblong shaped tubular part 5 which surrounds the receptacle 10 adjacent its upper edge. The cold water escapes from the perforations 7 at an angle of about forty-five degrees and striking against the adjacent surface of the receptacle 10 flows down its sides and effects relatively rapid cooling of the same and its contents. Generally speaking, a period of from twenty-five to thirty minutes is required to bring the contents of the receptacle to the desired temperature of from twenty to twenty-five degrees centigrade. Rapid cooling is essential in order to obtain a technically pure starting wort and a biologically pure fermentation. After the wort has been cooled as above described it is ready for inoculation. Inoculation is effected by introducing into the wort or other liquid nutrient a pure culture

which has been started in known manner. After such inoculation the development of the pure culture ferment in the receptacle 10 may be hastened by thoroughly aerating the same. This may be done by drawing off relatively small portions of the inoculated wort through the spigot 18 and pouring same back into the receptacle 10. This may be done three or four times in rapid succession. It may be noted that the receptacle or propagator 10 is designed to hold approximately sixty-two gallons, although my invention is not limited to this particular size of receptacle.

After a period of about twelve to twenty hours, the culture in the receptacle 10 will have developed sufficiently for use in the starting of larger amounts of wort. Assuming that the culture which has been developed is for use in a brewery, the contents are sufficient to start a brewing of from one hundred to one hundred and fifty barrels of wort between twelve and fifteen degrees centigrade.

In the above description I have had in mind the employment of the apparatus in the development of a culture or ferment for use in beer brewing, but it is to be understood that the apparatus is adapted for use in the manufacture of compressed or bakers' yeast, in the propagation of pure cultures of ferments for use in the manufacture of temperance or nonalcoholic cereal beverages with typical aroma and character; in the propagation of pure cultures for use in the manufacture of all dairy and creamery products; and in the manufacture of other ferments which produce a normally mild acidity in the finished product.

I claim:

1. In a cooling apparatus, the combination of a support comprising a plurality of legs, one at least of which is tubular, and a tubular member of desired shape secured to the upper ends of said legs and being in communication with and adapted to receive a cooling fluid from said tubular leg, said tubular member being provided with perforations upon its inner lower side, and a receptacle adapted to fit within and to be supported by the said tubular member.

2. In cooling apparatus, the combination of a receptacle, oval in cross section, a support upon which the said receptacle stands, a tubular member of oval shape surrounding the said receptacle adjacent its upper edge, said member being provided with perforations upon its inner, lower side, and means for supplying a cold liquid to the said member, said liquid being adapted to escape through the said perforations onto the surface of said receptacle.

3. In cooling apparatus, the combination of a receptacle, oval in cross section, having a closing lid and being provided with a

spigot adjacent its lower end, a portable support for said receptacle, said support comprising legs, a tubular member, oval in shape, surrounding the upper edge portion of and being adjacent to the said receptacle, said tubular member being supported upon the extended upper ends of the said legs, and being provided with perforations upon its inner, lower side, and one of 10 the said legs being tubular and being in

communication with the said tubular member, and means whereby a cooling liquid may be supplied to the said tubular leg and thence to the said tubular member, substantially as described.

15

In testimony that I claim the foregoing as my invention I have hereunto signed my name this 14th day of July, A. D. 1919.

MANFRED WAHL.
